UNITED STATES PATENT OFFICE.

JAMES H. MCPHAIL, OF NASHVILLE, TENNESSEE.

DESIGN FOR A CLASP.

SPECIFICATION forming part of Design No. 30,177, dated February 14, 1899.

Application filed January 4, 1899. Serial No. 701,167. Term of patent 7 years.

To all whom it may concern:

Be it known that I, JAMES H. MCPHAIL, a citizen of the United States, residing at Nashville, Tennessee, have invented and produced 5 a new and original Design for Clasps, of which the following is a specification.

In the accompanying drawings, Figure 1 is a perspective view of the clasp; Fig. 2, a sectional view.

10 The leading feature of the invention is the shape of the base-plate and wings, as clearly shown in the drawings. The base-plate A is of tapering shape and unbroken from end to end, and from its edges project wings B B,

also of tapering shape and coextensive as to 15 length with the base-plate. A series of points project inwardly from the wings B, as shown at C.

I claim—

The design for a clasp as herein shown and 20 described.

In testimony whereof I affix my signature in presence of two witnesses.

JAMES H. MCPHAIL.

Witnesses:

J. H. THOMAS,
E. W. FULLER.
